(57) **CLAIM**

The ornamental design for a combination ceiling fan and light fixture, as shown and described.

DESCRIPTION

FIG. 1 is a bottom perspective view of a combination ceiling fan and light fixture showing an embodiment in accordance with my design;

FIG. 2 is an enlarged top plan view of the combination ceiling fan and light fixture in accordance with my design;

FIG. 3 is an enlarged bottom plan view of the combination ceiling fan and light fixture in accordance with my design;

FIG. 4 is an enlarged side elevation view of the combination ceiling fan and light fixture in accordance with my design, the opposite side being a mirror image of that shown; and,

FIG. 5 is an enlarged front elevation view of the combination ceiling fan and light fixture in accordance with my design, the opposite side being a mirror image of that shown.

FIGS. 4 and 5 are identical except for the positioning of the fan blades.

The broken line showing of the canopy, support rod, and motor vent openings is included for the purpose of illustrating environmental structure and forms no part of the claimed design.
